UNITED STATES PATENT OFFICE.

MILTON F. WILLIAMS, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

SEPARATING AND REDUCING MECHANISM.

1,288,785.

Specification of Letters Patent. Patented Dec. 24, 1918.

Application filed July 12, 1915. Serial No. 39,425.

To all whom it may concern:

Be it known that I, MILTON F. WILLIAMS, a citizen of the United States, residing at the city of St. Louis, State of Missouri, have 5 invented a certain new and useful Improvement in Separating and Reducing Mechanism, of which the following is a full, clear, and exact description, such as will enable others skilled in the art to which it appertains to make and use the same, reference being had to the accompanying drawings, forming part of this specification.

This invention relates broadly to machines for reducing or comminuting various materials, and relates specifically to a machine which, in conjunction with the reducing or grinding process, selects the material which it is intended to be ground.

In the reduction of various materials, 20 such as the general run of stuff from which stock food is made, the material, in the aggregate, comprises a very general mixture running all the way from hulls, chaff and broken straw to grain. This mixture is ground into a meal of varying fineness for 25 stock food, poultry food and the like. It usually occurs that more or less refractory or unfriable material, such as pebbles and pieces of metal, find their way into the mixture, and if fed therewith to the grinder, 30 work damage to the machine.

It is the purpose of my invention to provide a machine which will have large reducing capacity for the amount of power employed, and which will operate, in conjunction with the reducing function, to separate the desired material from the undesired, feed the former to the reducing elements, and inhibit or prevent the feeding of the 40 latter thereto.

A further object of my invention is to provide a machine having the characteristics just described, which is particularly adapted for use by individuals of limited 45 experience with reducing machinery, so that it may be widely used with safety to both the operator and the machine itself.

A further object of my invention is to provide a machine having the characteristics described, which is capable of various 50 adjustments whereby selected constituents of the mixture fed thereto may be separated from the others, in conjunction with the reducing process.

A further object of my invention is to provide such a machine wherein the passage of the material through the machine may be regulated for varying the rate of reduction.

A further object of my invention is to provide a machine of the sort described wherein the collection and disposal of the finished product may be carried on in conjunction with the selecting and reducing process.

Other and further objects of my invention will be obvious or pointed out hereinafter.

In the drawings—

Figure 1 represents a front view of my improved machine with some of the parts thereof in vertical section;

Fig. 2 is a side elevation with parts in vertical section;

Fig. 3 is a detail of the intake terminal member.

As illustrated in these figures, 1 indicates a frame forming a suitable support for the various parts of a reducing mill 2, and for side brackets 4 which support a conveyer frame 5.

The mill includes a casing 6 forming a grinding chamber, and the hopper 7, which is separated from the grinding chamber by a cage 8 which is perforated, interrupted, or otherwise apertured to provide one or more discharge openings 8^a through which the finished product is discharged from the grinding chamber into the hopper 7. This cage constitutes one of the coating reducing elements, and co-operates with the movable reducing elements 9, here shown as hammers or beaters carried on the shaft 10, to reduce the material which it is desired to grind. The material is fed into the grinding chamber through a feed opening 11 in the manner hereinafter to be described.

A fan casing 12 is suitably supported on the frame 1, and co-operates with a centrifugal fan 14 which is carried on the shaft 10. A conduit pipe 15 leads from the discharge hopper 7 to the fan casing 12, opening thereto at the eye of the fan. A discharge pipe or conduit 16 leads tangentially from the fan casing to any suitable collecting device, such as the ordinary cyclone collector.

Mounted within the conveyer frame 5 are 105 drums or sheaves 17 which carry an endless conveyer belt 18, with which the sides 5^a of the conveyer frame co-operate to form a

trough having the conveyer belt as its bottom. Suitable gearing 19 which may be driven by belt 20 from shaft 10, operates to rotate one of the drums 17 so as to transmit 5 the conveyer belt 18.

Adjacent the drum 17, away from which the upper lap of conveyer belt 18 moves as it is transmitted, is a feed hopper 21 which is pivotally mounted on frame 5 so that its 10 lower or discharge end may be swung upwardly away from conveyer belt 18. In normal position, the lower or discharge end of hopper 21 lies adjacent to the upper surface of conveyer belt 18, but is spaced apart therefrom a little distance. The lower portion 15 of the side of hopper 21 which is on the side toward which the belt travels, is formed by a vertically adjustable slide 22, which is movable in a slideway 24, and which is retained 20 in adjusted positions by a clamping bolt 25. By upward or downward movement of slide 22 in slideway 24, the lower edge of the slide may be positioned nearer or farther away from belt 18. Material which is deposited 25 in hopper 21 is fed down onto conveyer belt 18, the amount of material discharged onto the conveyer belt being determined by the spacing of slide 22 relative to the belt. The material thus deposited on the belt is in a 30 uniform thin layer.

Leading into feed opening 11 is a feed conveyer pipe 26 which rises upwardly from a reduced end portion 26^a. Slidably mounted on the reduced end portion 26^a is a sleeve member 27 which is securable in various vertical positions on 26^a by means of any suitable securing means 28. Pivotally mounted on sleeve member 27 is nozzle member 29, which is held in operative position by the 35 catch 30 which may be released to permit nozzle member 29 being swung out of line relative to sleeve member 27. Adjustably mounted on nozzle member 29 are lip members 33, which are connected at their lateral 40 extremities by flexible sides 31, so as to form a terminal member communicating at its upper end with nozzle member 29, and opening at its lower end with a long and narrow orifice which is disposed in proximity to the 45 upper surface of conveyer belt 18. Suitable adjusting means 32 are provided whereby the width of the orifice of the terminal member may be varied. Reduced member 26^a is provided with a damper opening 26^b, the 50 effective size of which is determinable by the position of an adjustable damper 34. The foregoing forms a continuous pneumatic system as follows:

The fan 14 draws air in at the orifice of the 55 terminal member, up through reduced portion 26^a and through feed conduit 26 into the grinding chamber; then through the apertured cage into hopper 7, through hopper 7 and into pipe 15, thence into the fan casing, 60 whence it is expelled through discharge con-

duit 16. The amount of air taken in may be varied by adjustment of lip members 33 to vary the size of the intake opening, and the strength of the draft at the intake may be regulated by varying the effective size of 70 damper opening 26^b.

In operation, as stated above, material is fed from hopper 21 onto conveyer belt 18 in a thin uniform layer. By conveyer belt 18 it is transmitted to below the intake orifice 75 of the terminal member, where it is subjected to the draft of air being drawn into that orifice by the action of the fan. By vertical adjustment of sleeve member 27, and by adjustments of lip members 33 and damper 34 80 as above described, the effectiveness of this draft upon the material on the belt 18 may be varied so that it will pick up light stuff and leave heavy stuff. By such regulation, the device may be regulated to pick up the 85 chaff, hulls and broken straw and leave the grain, or it may be regulated to pick up all the desired material, leaving such heavy material as pebbles or metal. The heavy material which is not taken up by the draft 90 is left on the belt, by which it is transmitted to the point where the belt passes around the forward sheave 17, at which point it is discharged into a discharge chute 35. In case 95 some of the lighter pieces of metal are drawn into the intake orifice, they are not conveyed to the mill, but after rising in nozzle member 29 a short distance are permitted to fall back into the terminal member and onto the belt. All such retained foreign pieces may 100 be discharged from the terminal member by unlatching nozzle member 29 and swinging it back. The desired material, after being drawn into the intake orifice, is carried through feed pipe 26 into the grinding chamber. Here it is subject to the grinding action 105 of the reducing elements until sufficiently reduced to be discharged into hopper 7.

The arrangement described contributes materially to the rapidity of the reducing 110 process, and the passage of the material through the reducing machine. This is due to the fact that the feed is regular and uniform at all times. The machine is never gorged and never running empty, as the 115 uniform supply of material by conveyer belt 18 keeps the machine supplied continuously and uniformly. If the material is slow in reducing and going through the screen, the effectiveness of the fan to draw 120 material into the reducing chamber will be decreased, and, consequently, the machine will never be overloaded. In the second place, the passage of the material into the machine under draft, and the continuous 125 suction in the discharge hopper 7, prevent racing of the material with the beaters 9, and insure its discharge from the grinding chamber as soon as it is sufficiently reduced. Hence the material is not allowed to gather 130

in the reducing machine to impede the reducing process. The supply hopper is kept clear of finished product, as the meal is taken away by the fan as soon as it is drawn 5 into the hopper. Thus the machine is rendered dustless.

Suitable means may be provided for varying the speed of belt 18 so as to increase or decrease the rapidity of feed without varying the bulk or volume of the material presented to the intake orifice. The adjustment of the slide 22, as above described, provides for varying the volume of the stream of material fed to the intake, while 15 the adjustment of lip members 33, sleeve member 27, and damper 34 permit variations in the aspirative effectiveness of the device whereby its selective function and its reducing function may be affected.

20 This device forms a very efficient separating and reducing system which can be operated on very little power, as the operation of the fan does not require additional power, and in fact lessens the amount of 25 power required to operate the mill by securing a uniformity of feed and an immediate withdrawal of reduced material from the grinding chamber. The power required to operate the conveyer belt is inconsiderable. This arrangement also provides an 30 ideal machine for very wide and general usage, as it is substantially "fool-proof." It cannot be gorged, and it cannot be put 35 out of commission by the introduction of refractory foreign material. There is no waste of product, as it is all handled directly from the reducing chamber to the collecting device. It is very simple and inexpensive to install, as it requires no 40 external shafting, and but the single drive belt to transmit power to the operating shaft.

I am aware that the device and its component parts are capable of changes and

modifications departing from the embodiment herein shown and described, without departing from the spirit and scope of the invention.

What I claim is:

1. In a separating and feeding mechanism, the combination of a chamber provided with a feed inlet and a screened outlet for reduced material, feeding mechanism for continuously feeding material to said inlet, and aspirative means operable to discharge reduced material from the chamber through the screen and to select material from said feeding mechanism and convey the selected material to the chamber, which last mentioned means includes a suction 60 nozzle, the mouth of which is adjustable in width so as to vary the volume of material taken up by said nozzle, said feeding mechanism being operable to discharge the material remaining thereon. 65

2. In a combined separating and feeding mechanism, the combination with a chamber having a foraminous portion for the discharge of reduced material and an inlet for the supply of unreduced material, of means 70 for feeding material continuously to the inlet in uniform volume, and aspirative means effective through the foraminous portion of the chamber to draw unreduced material from the feeding means into the chamber against the influence of gravity and reduced material out of the chamber, which aspirative means includes a suction nozzle, the intake opening of which is adjustable in width so as to vary the volume of material taken up by said nozzle. 75

In testimony whereof I hereunto affix my signature in the presence of two witnesses, this twenty eighth day of June, 1915.

M. F. WILLIAMS.
